United States Patent Office

Des. 220,906
Patented June 15, 1971

220,906

CHAIR OR SIMILAR ARTICLE

Donald J. Borichevsky, Wells, Va., assignor to The Tele-
scope Folding Furniture Co., Inc., Granville, N.Y.

Filed Apr. 16, 1969, Ser. No. 16,815

Term of patent 14 years

Int. Cl. D6—01

U.S. Cl. D15—1

FIG. 1 illustrates a perspective front view of a chair or similar article incorporating a frame of the invention as a back rest and as a seat;

FIG. 2 illustrates a rear perspective view of the chair of FIG. 1;

FIG. 3 is an enlarged plan view showing the seat in greater detail;

FIG. 4 illustrates a cross-sectional view of the frame taken on line 4—4 of FIG. 3; and

FIG. 5 illustrates a partial view taken on line 5—5 of FIG. 4 showing an insert of patterned material within the coiled transparent tubing.

I claim:
The ornamental design for a chair or similar article, as shown and as described.
